(57) CLAIM

The ornamental design for a bottle, as shown and described.

DESCRIPTION

FIG. 1 is a first side view of a first embodiment of a bottle showing our new design;

FIG. 2 is a second side view thereof opposite to the first side view;

FIG. 3 is a top view thereof;

FIG. 4 is a front view thereof;

FIG. 5 is a rear view thereof;

FIG. 6 is a bottom view thereof;

FIG. 7 is a bottom perspective view thereof;

FIG. 8 is a first side view of a second embodiment of a bottle, with an unclaimed cork disclosed in broken lines, which forms no part of the claimed design, wherein the design features of FIGS. 3-7 are incorporated by reference therein and made a part thereof; and

FIG. 9 is a second side view opposite to the first side view of FIG. 8, with an unclaimed cork disclosed in broken lines, which forms no part of the claimed design, wherein the design features of FIGS. 3-7 are incorporated by reference therein and made a part thereof.

FIG. 10 is a side view of the bottle top feature portion shown removed from the bottle visible in FIGS. 8-9, with an unclaimed cork disclosed in broken lines, which forms no part of the claimed design;

FIG. 11 is a first side view of the bottle of FIG. 8 shown with the bottle top feature portion of FIG. 10 removed, wherein the design features of FIGS. 3-7 are incorporated by reference therein and made a part thereof; and,

FIG. 12 is a second side view of the bottle of FIG. 8 shown with the bottle top feature portion of FIG. 10 removed, wherein the design features of FIGS. 3-7 are incorporated by reference therein and made a part thereof.

The broken lines in FIGS. 8-10 illustrating a cork depict environment and form no part of the claimed design. All other broken lines and the spaces contained within them depict portions of the bottle that form no part of the claimed design.

(57) CLAIM

The ornamental design for a bottle, as shown and described.

DESCRIPTION

FIG. 1 is a first side view of a first embodiment of a bottle showing our new design;

FIG. 2 is a second side view thereof opposite to the first side view;

FIG. 3 is a top view thereof;

FIG. 4 is a front view thereof;

FIG. 5 is a rear view thereof;

FIG. 6 is a bottom view thereof;

FIG. 7 is a bottom perspective view thereof;

FIG. 8 is a first side view of a second embodiment of a bottle, with an unclaimed cork disclosed in broken lines, which forms no part of the claimed design, wherein the design features of FIGS. 3-7 are incorporated by reference therein and made a part thereof; and

FIG. 9 is a second side view opposite to the first side view of FIG. 8, with an unclaimed cork disclosed in broken lines, which forms no part of the claimed design, wherein the design features of FIGS. 3-7 are incorporated by reference therein and made a part thereof.

FIG. 10 is a side view of the bottle top feature portion shown removed from the bottle visible in FIGS. 8-9, with an unclaimed cork disclosed in broken lines, which forms no part of the claimed design;

FIG. 11 is a first side view of the bottle of FIG. 8 shown with the bottle top feature portion of FIG. 10 removed, wherein the design features of FIGS. 3-7 are incorporated by reference therein and made a part thereof; and,

FIG. 12 is a second side view of the bottle of FIG. 8 shown with the bottle top feature portion of FIG. 10 removed, wherein the design features of FIGS. 3-7 are incorporated by reference therein and made a part thereof.

The broken lines in FIGS. 8-10 illustrating a cork depict environment and form no part of the claimed design. All other broken lines and the spaces contained within them depict portions of the bottle that form no part of the claimed design.
